UNITED STATES PATENT OFFICE.

VICTOR A. LINGLE, OF LEWISBURG, PENNSYLVANIA.

COIL-BOX.

1,353,116.

Specification of Letters Patent. Patented Sept. 14, 1920.

Application filed March 5, 1920. Serial No. 363,557.

To all whom it may concern:

Be it known that I, VICTOR A. LINGLE, a citizen of the United States, residing at Lewisburg, in the county of Union and State 5 of Pennsylvania, have invented new and useful Improvements in Coil-Boxes, of which the following is a specification.

This invention relates to improvements in motor vehicles and has particular relation 10 to a box or casing for inclosing the spark coils of the ignition system, so as to reduce the danger of the short circuiting of the conductor wires through water entering the hood during a heavy rain.

15 Another object of the invention is the provision of a coil box in which the coils and coil terminals are readily accessible, so that in the event of trouble, the parts may be easily and quickly repaired.

20 With the above and other objects in view, the invention includes the following novel features and details of construction, to be hereinafter more fully described and illustrated in the accompanying drawings.

25 In the drawings:—

Figure 1 is a perspective view of the improved coil box shown in position upon a fragmentary portion of an automobile instrument board.

30 Fig. 2 is a transverse sectional view.

Fig. 3 is a vertical section through the coil terminal compartment or housing.

Fig. 4 is a horizontal section.

Fig. 5 is a front elevation showing the 35 cover partly removed.

Referring to the drawings in detail, wherein like characters of reference denote corresponding parts, the invention comprises a coil box which is designated in its entirety 40 by the reference character 10. The box is divided into a main coil compartment 11 and a terminal compartment 12. The coil compartment 11 is of elongated rectangular shape and is provided with an open top 45 which is closed by a lid or cover 13, while the terminal compartment 12 has extended therefrom a conduit 14. This conduit projects upwardly from the top of the terminal compartment 12 and extends across the top 50 of the coil compartment 11 and in order that the lid or cover 13 of the coil compartment may be removed, the said lid or cover is slidably mounted upon the coil compartment so that it may be moved longitudinally 55 of said compartment in its removal. In order to hold the lid or cover 13 in position,

there is provided a spring catch 15, while the lid or cover has secured thereto a handle 16 for convenience in removing.

The terminal compartment 12 extends 60 along one side of the coil compartment 11, and is of less height than said compartment 11, and forms an extensional projection of the coil box, with the side wall 17, of said box forming one of the side walls of the 65 compartment 12. This side wall 17 is provided with a plurality of openings 18 for the passage of the coil terminals, which connect with the conductor wires leading to the spark plug of the engine and to the battery 70 and magneto. In addition, the wall 19 of the terminal compartment 12 is provided at each end with an opening 20 by means of which access may be had to the interior of the compartment 12 for the purpose of adjusting the coil terminals. These openings 20 are normally closed by a hinged door 21, which is provided with a suitable latch or lock 22. The wall 19 is further provided with openings 23 to permit of the positioning of the usual ignition switch, the wires 75 of which extend through an opening 24.

The invention is susceptible of various changes in its form, proportions and minor details of construction and the right is here- 80 in reserved to make such changes as properly fall within the scope of the appended 85 claims.

Having thus described my invention what I claim as new is:

1. A coil box comprising a main coil compartment, a removable cover therefor, a terminal compartment and normally closed 90 openings for said terminal compartment.

2. A coil box comprising a main coil compartment, a removable cover therefor, a terminal compartment and normally closed 95 openings for said terminal compartment, and a wire conduit leading from the terminal compartment over the top of the coil 100 compartment.

3. A coil box comprising a main coil compartment, a removable cover therefor, a terminal compartment extending along one side of the coil compartment and having open- 105 ings in the dividing walls, a wire conduit leading from the top of the terminal compartment over the top of the coil compartment, and door controlled openings for the terminal compartments.

In testimony whereof I affix my signature.

VICTOR A. LINGLE.
